FIG. 8.

This technical drawing illustrates a mechanical assembly, likely a cylinder or piston rod assembly. The drawing shows a central vertical rod with various components attached. A callout box in the upper left corner provides a detailed view of a section of the assembly, showing a cross-section with dimensions 80¹, 81, 82, and 83. The main assembly features a central vertical rod with various components attached. Key components include:

- Top plate: 21
- Top cap: 43
- Top rod: 45
- Top bearing: 46
- Top piston: 44¹
- Top piston rod: 44²
- Top piston rod bearing: 34

ABSTRACT OF THE DISCLOSURE

Transparency projection apparatus including separate 15 motors for indexing a magazine which houses the transparencies and for driving a slide which moves the transparencies from the magazine to a projection position and back again, the magazine being provided elements co-operating with a circuit to control the operation of the 20 magazine and slide.

This invention relates to transparency projectors which are loaded by a magazine containing a number of separate transparencies, the transparencies being returned to the magazine in the same sequence after projection.

Such magazines have the double advantage of rapid and easy loading of the projector and a well-ordered and compact arrangement of the transparencies. Projectors for transparencies stored in a magazine comprise means, specifically a slide, which extract the transparencies from the magazine one by one to bring them into a position of co-operation with the optical system of the projector and then return them to the position that they previously occupied in the magazine. They generally also include a system by means of which, after each removal and return of a transparency, the magazine is so moved that the position theoretically occupied by the next transparency in the magazine occupies a position for co-operating with the slide.

In other words, the magazine is moved by a distance corresponding to the distance between the successive transparency recesses in the magazine. This stepwise movement of the magazine is produced by mechanical means subject to the slide movement so that during a transparency removal and return cycle, or more exactly a cycle of the return of a transparency into the magazine and the removal of the next transparency from the magazine, the latter is never moved more than one step.

In the most refined equipment, this step may be produced at the user's will either in the same direction as the previous direction or in the opposite direction, inter alia to allow projection of a series of transparencies in the reverse sequence to that in which they were just projected.

The disadvantage resulting from this single possibility of the re-projection a series of transparencies without manual intervention is one of the reasons which has induced manufacturers to make the magazine in the form of a turret for continuous projection of series of transparencies in the same sequence.

Because the movements of the magazine are mechanically controlled by the reciprocating movement of the slide it has only been necessary to control the slide by an electric motor to render all the projector loading operations automatic.

Although this development would appear to be quite logical, it entails numerous disadvantages, which the present invention intends to obviate.

2

A first object of the invention, which consists essentially in that the element which acts in known manner on the magazine to move the same is controlled by a separate power source independent of any driving action of the slide which moves the transparencies into the projection position from the magazine and vice-versa, is to provide an electromechanical system wherein the movement of the transparency magazine with respect to the loading slide is free from any travel limitation to a fraction of the total movement of the magazine.

A second object is to provide a system for moving the magazine with respect to the loading slide, such system being rendered operative simply by the slide being brought into the disengaged position.

A third object is to provide a system for moving the magazine with respect to the loading slide to comply with information means borne by the magazine or by a carriage acting as a support for the magazine.

An important feature of the information system with which the magazine or a supporting carriage is provided to control the movement of the magazine with respect to the loading slide is that the elements of such system occupy an operative position either permanently or as an automatic result of other elements, for example the presence of a transparency in the magazine recesses, or as the result of manual intervention on the information elements borne by the magazine or on external elements co-operating with the magazine information elements.

Another object of the invention is to provide an electromechanical drive system to produce a reciprocating movement of the loading slide and adapt it to interrupt its action for an indeterminate period, inter alia to enable the magazine moving system to be controlled by the information borne by the magazine and to resume its action as soon as rendered necessary, inter alia in response to information elements borne by the magazine.

According to the invention, a direct drive system is provided for the reciprocating movement of the loading slide, the motor being in direct engagement with the slide by friction or by gearing and a rack.

The control system for the reciprocating movement of the loading slide comprises electromechanical means which permit manual operation of the slide in any position of the cycle.

An important advantage and a consistent characteristic is that the loading system elements which have a driving or controlling action may be mounted on an assembly plate so as to be adapted to being electrically connected through the agency of printed circuits, this giving an economic advantage as regards production.

In order that the invention may be more readily understood, various embodiments of systems according to the invention will be described hereinafter with reference to the drawing, both as regards construction and operation.

The inventive features already mentioned hereinbefore and others not mentioned in the preamble will be apparent from this description and this illustration.

In the accompanying drawings:
FIG. 1 is a plan view showing a magazine control system according to the invention with a selection device.

FIG. 1A is a section on line 1A—1A in FIG. 1.
FIGS. 2, 3 and 4 are sections respectively on lines II—II; III—III; IV—IV in FIG. 1.

FIGS. 5 to 11 show the slide driving system.
FIG. 5 is a sectional elevation on line V—V in FIG. 6.
FIG. 6 is a sectional plan view on line VI—VI in FIG. 5.

FIG. 7 is a vertical section on line VII—VII in FIG. 8, and FIG. 8 is a section on line VIII—VIII in FIG. 7.

FIGS. 9-11 are views of the slide driving system similar to that in FIG. 8 but in different operative positions.

FIGS. 12 and 13 are respective sections on the lines XII—XII and XIII—XIII in FIG. 5.

FIG. 14 is a plan view showing the magazine in the position occupied before operation starts.

FIG. 15 is a section on line XV—XV in FIG. 14.

FIG. 16 is a section on line XVI—XVI in FIG. 15.

FIG. 17 is a view similar to FIG. 14, the magazine having been manually brought against the push member of the slide.

FIG. 18 is a section on line XVIII—XVIII in FIG. 17.

FIGS. 18 and 19 are views similar to FIGS. 15 and 16 with the elements in other positions.

FIG. 20 is a similar view to FIG. 14, the magazine having been moved into a position in which the transparency selected is at the required position for movement into the optical axis of the projector.

FIGS. 21, 22 and 23 are explanatory views.

FIGS. 24 to 27 are details of the magazine.

FIGS. 28 and 29 show how the printed circuits may be made.

FIGS. 30 to 38 are electric circuit diagrams.

FIGS. 39 to 43 relate to a variant with selection.

FIG. 43 and FIGS. 44 to 48 relate to other variants with selection.

FIGS. 49 to 52 refer to a conventional magazine resting on a carriage.

FIG. 52A shows another arrangement of the magazine.

FIGS. 53 and 54 are views similar to FIGS. 1 and 1A relating to a simplified embodiment without electrically controlled selection.

FIGS. 55 to 58 show embodiments of the magazine without selection.

FIG. 59 is a circuit diagram applicable to an embodiment without electrically controlled selection.

Reference 21 in the accompanying drawings denotes a frame formed with a channel 22 which is parallel to the optical axis of the projector and in which the transparency magazine 23 moves (FIGS. 1 and 1A).

Along one side on the outer surface of its base the magazine 23 (FIGS. 24-27) bears a rack 25 with vertical teeth. This magazine moves in the channel 22 and as it does so it bears against a rail 26 forming part of a guide 27 with an inclined inner surface 27¹, such guide being formed along one side 22¹ of the channel 22 (FIGS. 1A-5 and 20) and a rail 29 forming part of a guide 28 which also has an inclined surface 28¹, the two rails 26 and 29 rest on the base 22³ of the channel 22 (FIG. 5).

A front projection 30 and a rear projection 31 (FIGS. 17 and 27) which are provided longitudinally on the base of the magazine and which are laterally offset from one another rest on the rail 29.

The guides 27 and 28 are interrupted at the middle at registering positions 32-33, slots 34-35 being formed in the sides 22¹ and 22² of the channel 22 in these positions (FIGS. 2 and 8).

A pinion 36 is provided in the interrupted part of the guide 27 and is secured to the vertical shaft 37 of a motor 38 which rests by legs 39 on the frame 21 (FIG. 2).

These slots 34-35 permit the passage of push elements 41 and 41¹ (FIGS. 1 and 2) each connected by a vertical arm 42-42¹ and a Z-section 42-43-44 (FIGS. 2 and 12) making up the loading slide which moves in guides 44¹-44²-44³ (FIGS. 2 and 11-13) which offer low frictional resistance.

The object of the push element 41 is to move the transparencies 40 from the magazine 23 to the optical axis of the projector while the push element 41¹ pushes the transparency back into the magazine, these two operations being carried out by the reciprocating displacement of the loading slide.

A flat 45 is secured to the vertical arm 44 of the Z

section (FIGS. 5 and 6) in extension of the latter and bears an angle-section 46 with a flexible strip 47 clamped between a roller 48 secured to the shaft 49 of a motor 50 and a roller 51 (FIG. 5) mounted freely on a pivot 52 borne by a lever 53 articulated at one end about a pivot 54 borne by a bracket 55 forming part of the frame 21 and loaded by a spring 56 one end of which is secured to a fixed point of the frame.

The vertical part 57 of a Z-section is secured to the flat 45, the top horizontal arm 57¹ of the Z having at the bottom a rail 57² sliding in a support 44³ secured to the frame, the bottom horizontal arm being continued in the form of lugs 59-60 each bearing a stud 61-62 (FIGS. 6 and 13).

The bottom horizontal arm 58 has a projection 63 (FIG. 8) over a certain length of the bottom part to act on a reversing switch 64 intended to reverse the direction of rotation of the motor (FIGS. 6 and 8).

This reversing switch (FIG. 11) comprises a disc 65 of insulating material which can oscillate about a pivot 66 (FIG. 10) connected to the frame 21; two flexible strips 67-68 are fitted in the periphery of this disc, the end of the strip 67 bearing a stud 69 for co-operation (as will be explained hereinafter) with the ramps 70 and 71 formed at each of the ends of the projection 63.

The strip 68, which is bent over at the end 68¹, is acted upon by the stud 62 or the stud 61. On each side of the strip 67 there are provided stops 72-73 and conductive strips 74-75 secured at 76-77 and bearing contact studs 78-79 (FIG. 8).

Stud 61 (FIG. 6) may act on the movable element 80-81 to close a switch which is normally held open by a spring 80¹.

The system also includes a switch 83 (FIG. 16) controlled by a three-arm lever 84-85-86 rockable about a fixed horizontal pivot 87 (FIGS. 15 and 16).

The arms 84 and 85, which are laterally offset from one another, each engage alternately and respectively in apertures 88 and 89 formed with the same lateral offset in the frame 21 and in the rail 29 of the guide 28; arm 84 thus co-operates with the projection 31 and arm 85 co-operates with the projection 30 of the magazine 23 (FIG. 15).

The arm 86 (FIGS. 15 and 16) bears a small magnet 90 situated between soft iron studs 91-92 on flexible strips 93-94. Strip 93 bears a contact 95 co-operating with a contact 96 on a flexible strip 97; strip 94 has contacts 98-99 on opposite surfaces for co-operation with other contacts 100-101 on flexible strips 102 and 103.

For determination of the position of the magazine in the channel 22 for selection of the transparency for projection, the side end of an insulating plate 104 (FIGS. 3 and 4) is provided with a conductive band 105 bearing an angle section 106-107 to the vertical flange of which are connected strips 108 whose free end can co-operate with a conductive U-section rail 109 connected by a lead 109¹ to the switch 81-82 (FIG. 30).

Each strip 108 passes through an aperture 108¹ of a rocking lever 110 which continues in the form of a lever 110¹ which below the strip 108 bears a strip 111 which can be brought into contact with a conductive band 112 provided for each of the strips on the insulating plate 104 and respectively connected to a conductive strip 113 (FIGS. 3, 4 and 28).

These conductive strips 113 (FIGS. 1, 6, 8, 23, 28) are aligned transversely in the base of the channel 22 and can co-operate via a transverse slot 114 with electrically conductive projections 115 provided on the base 116 of the magazine on which they are longitudinally and transversely offset, i.e. disposed along a diagonal of the surface of the base which is itself of conductive material.

The base of the magazine has at the front a conductive transverse tongue 117 which can simultaneously touch all the contacts 113 (FIGS. 17 and 23) in the initial position of the magazine.

The conductive base 116 is permanently connected electrically to a sliding contact 118.

The diagram in FIG. 30 shows the power supply leads 120-121, of which the former runs to a terminal 122 of a press-button 123 co-operating with a fixed contact 124.

Conductor 121 runs to the strips 94 and 97 of the reversing switch 83.

Contact 124 is connected firstly via lead 125 to strip 67 of reversing switch 64 and secondly via lead 126 to the sliding contact 118.

A lead 127 extends from lead 120 to terminals 76-77 of the strips 74 and 75 of the reversing switch 64.

Leads 128-130 respectively connect the terminals 129 and 131 of motor 50 to stop contacts 72 and 73 of the reversing switch 64.

A lead 133 extends from terminal 132 of motor 50 to strip 93 of the reversing switch 83.

Terminals 134-135 of motor 38 are respectively connected via leads 137-138 to strips 102-103 of the reversing switch 83 while terminal 136 is connected to contact 82 via a lead 139.

A lead 140 extends from lead 120 to the conductive band 105 for the rocking selection levers 110.

In the example illustrated, the motors 38 and 50 are multipole and hence reversible slow-speed motors which can be rotated in either direction.

For a description of the operation of the system, it will be assumed that the magazine 23 is in the inoperative position (FIG. 14), in which its rack is disengaged from the pinion 36 and its conductive base is in contact with neither the sliding contact 118 nor with the conductive strips 113, the three-arm control lever 84-85-86 being either in the position shown in FIG. 15 or the position shown in FIG. 18.

If, for example, it is required to project transparency number 4 in the magazine, the lever 110 corresponding to such number is rocked in the direction of arrow F (FIG. 30); the strip 108 of this lever will thus touch the base of the U-section conductive rail 109 while strip 111 will close the contact with the conductive band 112 (FIG. 31) which corresponds thereto.

The magazine 23 is then brought manually from the disengaged position shown in FIG. 14 into the starting position shown in FIG. 17; the transverse conductive tongue 117 of the magazine will touch all the selection contacts 113 and as a result current is fed to the terminal 131 of the motor 50 via 126-125-67-73 and 130. This position also corresponds to the position in which the front of the magazine is brought into contact with the push element 41 of the loading magazine if the latter is in the position shown in FIG. 17. In this starting position the rack 25 is in mesh with the pinion 36.

During the process of bringing the magazine into the starting position, projection 30 has rocked the three-arm lever 84-85-86, which occupied the position shown in FIGS. 15-16, and which now occupies the position shown in FIG. 18; magnet 90 is thus rotated into the position shown in FIGS. 19-31 so that the stud 91 is attracted and sticks to the magnet 90 while strip 93 is so curved that the contacts 95-96 touch; the power supply current from the lead 121 is applied to the terminal 132 of the motor 50 via the lead 133, such motor driving the slide (FIG. 31).

When the motor 50 receives current it rotates in the direction of arrow F₁ (FIG. 31) and shaft 49 rotates the roller 48 and causes the slide to be withdrawn via the tongue 47 connected thereto (FIG. 10); during this withdrawal (FIG. 11) components 63 is driven with the slide and acts via its ramp 71 on the stud 69 of the tongue 67 which will touch the contacts 79 so that the current originating from 120 (via 127, 77, 75, 79) continues to be supplied to terminal 131 via 67, 73, 130.

At the end of the movement of the slide (FIGS. 8 and 32), stud 69 leaves the edge of component 63 and enables

the reversing switch 64 to pivot on the pivot 66 because the stud 62 acts on the tongue 68 of reversing switch 64 and brings it into the position shown in FIG. 32; the tongue 67 separates the contacts 67-73 with resultant stoppage of the motor 50; also, at the end of its movement the stud 61 pushes on the lever 80 and closes the switches 81-82 so that current is supplied to terminal 136 of motor 38 via lead 139; motor 38 starts to rotate in the direction of arrow F₃ (FIG. 32) and advances the magazine 23 until a contact 113 is touched by the projection 115 corresponding to the transparency selected (FIG. 33). Current is then applied to motor 50 via the conductive strip 116, sliding contact 118, leads 126 and 125, strip 67, stud 72, lead 128 and terminal 129. Motor 50 rotates in the direction of arrow F₂ (FIG. 33).

As a result of the movement of the slide (arrow F₅-FIG. 33) and of the stud 61 which no longer bears on 80, the circuit of motor 38 is broken at 81-82 and this motor stops.

Projection 115 has passed over contact 113 (FIG. 34) only to start the motor 50, which continues to be fed by the action of the projection 63 which at the beginning of its movement rubs against the stud 69 and bends the tongue 67 thus bringing the tongue into contact with the contacts 78 and 72. Current continues to be applied to the terminal 129 of motor 50 via the lead 128; the motor continues to rotate until the transparency is brought into the projection position.

Stud 69 is then returned to the position shown in FIG. 35 and motor 50 is stopped.

To conclude the projection of the transparency, press button 123 is actuated (FIG. 36), the current is supplied to motor 50 via 120-122-123-124-125-67-73-130 and 131. This time the motor 50 rotates in the direction of arrow F₁; the transparency is returned into the magazine and at the end of the movement the motor 50 stops by the action of the switch 64; contacts 81-82 close and motor 38 starts to rotate in the direction of arrow F₃ (FIG. 37) and advances the magazine until projection 31 on the latter passes arm 84 of lever 84-85-86 to rock the latter and act on the reversing switch 83 which is returned to the position shown in FIG. 38, in which the motor 38 is fed to rotate in the direction of arrow F₄; since switch 95-96 is open, the motor 50 cannot receive current and this prevents any transparency loading operation irrespective of which selection levers 110 are in the operative position during movement of the magazine in the return direction in which they cause the magazine to move in the rearward direction into the starting position.

This rearward movement of the magazine continues until projection 30 again rocks the three-arm lever 84-85-86 in the position shown in FIG. 18.

As a result of this rocking movement the direction of rotation of motor 38 is reversed. Magazine 23 thus moves forward (the system occupies the position shown in FIG. 32) until the projection 115 of the selected transparency or transparencies (in this case number 4)—if such selection is maintained—contacts the contact 11. The system is then shown in FIG. 33; the transparency will be brought into the projection position and the cycle of operations can recommence as described hereintobefore if the press button is actuated as already explained.

To facilitate the description of operation, the cycle of operations has been described solely in connection with the selection of a single transparency, in this case transparency number 4.

Of course if a plurality of or all the selection levers 110 were brought into the operative position and if a plurality of or all the contact strips were rendered operative, the starting pulses for the motor 50 produced as the various conductive projections 115 encounter the corresponding contact strips 113 would result in repetition of the loading operation described for selection of number 4 as the magazine moves forward from the rear (motor 38, direction F₃).

Since it is impossible for the transparency to be brought into the projection position because of the opening of the contacts 95-96 when the reversing switch 83 is in the position shown in FIG. 38 during movement of the magazine to the rear, the repetition of the selections made always occurs in the same sequence, and this is a distinct advantage for the continuous and repeated projection of a specific number of transparencies, for example for publicity purposes, the projection end contact being closed via a time switch.

FIGS. 39 to 42 relate to a variant wherein the base of the magazine 23 is not conductive (reference 116) and the projections (reference 115¹) disposed diagonally on the bottom surface of the base are also non-conductive.

Lead 126 is connected to a plate 140 above which there is a row of contact strips 141 disposed along the longitudinal axis of the channel 22 and secured at one of their ends by a plate 142 which insulates them from the plate 140. At their free end these strips have a bent portion 143 so that the action of the projection 115¹ corresponding to the selected transparency on the bent portion 143 causes end 144 of the corresponding strip 141 to come into electrical contact with the plate 140 and the entire system then operates as explained in connection with FIGS. 30 to 38.

In the case of FIG. 43, the base 145 of the magazine 146 bears a number of strips 147 equal to the number of transparency recesses, such strips having bent portion 149, while the frame is provided with a switch 148, for example a microswitch. When a transparency 150 is introduced into a recess of the magazine 146, the transparency acts on the bent portion 149 of the corresponding strip 147 and brings its end 151 into a projection position such that on movement of the magazine 146 said end 151 can act on the control arm 152 of the switch 148 and close the latter, thus resulting in operation as explained hereinbefore, except that it applies only to compartments which contain transparencies.

With regard to the embodiment shown in FIG. 43, the system operates without selection with the diagram shown in FIG. 59, but of course it would be enough to maintain the selection system as described hereinbefore and to control the exit of the projection 115¹ in FIGS. 39 to 41 by the strips, e.g. reference 147 (FIG. 43) to maintain the advantage of electric selection while maintaining the advantage of the possibility of operation reserved for compartments provided with a transparency.

In the case of FIGS. 44 and 45, push elements 153 are provided along the rear surface of the magazine 23, each push element corresponding to a transparency recess and being vertically slidable. These push elements 153 occupy the position 153² in the inoperative state and are brought into the operation position (positions 153¹ and 153³) by vertical thrust so as to act in the same way as the projections 115¹ in FIGS. 40 and 41 to operate the system by closure of a contactor of the type 141-141¹ as illustrated in FIG. 40; the diagram of the system may in that case be limited to the diagram shown in FIG. 59.

The projection 154, which may occupy an inoperative and an operative position may of course be brought into and held in the manual operative position by devices other than the device shown in FIG. 44, without thereby departing from the scope of the invention.

In FIGS. 46-48, the magazine 23 is also provided with push elements 153 as in FIG. 44, but operation is started through the agency of a photo-electric cell 156 and a lamp 157 so disposed that in the operative position the end of the push element 153 interrupts the passage of the light emitted by the lamp 157. This system of detecting projections by a photo-electric cell can of course be used in the other projection combinations, inter alia in the case of fixed projections.

FIGS. 49 to 52 and 52A relate to a case in which a standard commercial magazine 158 rests between two stops 160 on a carriage 159 provided with one of the

systems of projections described hereinbefore, the stops 160 providing a predetermined relationship between the transparency recesses in the magazine and the operative elements of the carriage including any concerned with possible selection.

The carriage 159 bears inter alia a rack 25 actuated by a gearwheel 36 controlled by the motor 38 and in the example illustrated the base of the carriage 159 has on its bottom surface projections 115 disposed in the same way as those provided in FIG. 27 on the inside surface of the magazine base.

In all the embodiments described hereinbefore, the magazine or carriage acting as a support for the magazine is provided with an information device for controlling the movement and stoppage of the magazine with respect to the loading slide, and the elements used for selection are brought into the operative position either after an operation for such purpose or as an automatic result of other factors, for example the presence of a transparency in the recesses of the magazine.

The invention naturally covers cases in which the magazine is provided with permanent information elements to start operation for each of the successive transparency recesses provided in the magazine in one direction of movement of the latter while retaining the advantage that the magazine information elements may be kept inoperative in the other direction of movement of the magazine, so that movement of the magazine in this latter direction is not limited to a fraction of the total movement of the magazine.

The device provided for operation with magazines provided with permanent information elements for each of the transparency recesses may of course be designed to operate with magazines whose information elements may be selected in the operative position and hence occupy either an operative or an inoperative position.

FIGS. 53 and 54 show such a simplified system wherein the selection device illustrated inter alia in FIGS. 1, 1A, 3 and 4, has been eliminated.

In FIG. 55, the magazine 23 is embodied as in FIGS. 24 to 27 and the projections 115 disposed diagonally on the bottom surface co-operate with a strip 161 replacing the various strips 113 in FIGS. 14, 23 and 30.

A sliding contact 118 is in permanent contact with the conductive coating 116 provided on the inner surface of the magazine base.

On each advance of the magazine by the distance between two projections 115 corresponding to the distance between two transparencies, the circuit will be closed through 118-116-115-161.

In the case of FIG. 56, the projections 115 are not disposed diagonally, but are situated along the edge of the base, but operation remains the same as in the case of FIG. 55.

In FIG. 57, the projections 115 are moulded with the base and are non-conductive. On the required stepwise advances, the various projections 115 act successively on a lever 162 actuating a switch, for example a microswitch 163.

The embodiment shown in FIG. 58 differs from FIG. 57 only in that the projections 115 are disposed along one edge of the base.

FIG. 59 shows the diagram in the case of an embodiment without electrically controlled selection.

As shown in FIGS. 28 and 29, the elements which have a driving or control action may be mounted on an assembly plate, e.g. 104, (FIG. 28), so as to be electrically connected via printed circuits.

Of course, the embodiment details as described and illustrated are given solely by way of example and have no limiting force as to the scope of the various essential characteristics of the system.

Numerous constructional variants may be introduced without departing from the invention.

What I claim is:

1. A motor-driven transparency projection apparatus comprising a transparency magazine adapted for holding a plurality of transparencies, a reciprocally movable slide adapted for moving said transparencies between the magazine and a projection position in the projector, said slide having a first position in which it does not interfere with movement of the magazine and a second position in which it interferes with such movement, said magazine also including a plurality of stoppers adapted for being activated in a predetermined sequence, a first electric motor coupled to said magazine for indexing the same and a second electric motor separate from the first motor and adapted for moving said slide, means for connecting said stoppers in electric connection with said second motor, a circuit for the second motor comprising a switching member responsive to the said slide and being adapted for closing the said circuit when the slide is in said first position, said slide having a reciprocating cycle between said positions during which cycle transparencies are moved by the slide between the magazine and said projection position, said slide being related to said magazine such that said first position is achieved immediately after reintroduction of a transparency into the magazine, the closure of the circuit being effected only with the slide in said first position, and means whereby the slide interrupts its own movement in said first position in which it closes said circuit.

2. A system according to claim 1 wherein said first motor is of the multiple-pole type adapted for operating at a slow speed of rotation.

3. A system according to claim 2, wherein the first electric motor includes a rotor constituted by a plurality of permanently magnetized poles.

4. A system according to claim 1 wherein said first and second motors each include a stator and rotor which comprise a plurality of poles arrayed to insure substantially instantaneous operation when voltage is applied, relatively slow rotation, and substantially immediate stoppage when the voltage is interrupted.

5. A system as claimed in claim 1 comprising means for controlling the slide for moving transparencies from the magazine into the projection position and back into said magazine, including a friction roller driven by the first motor, a second roller urged against the first roller and a flexible strip clamped between the two rollers and coupled to the slide.

6. A system according to claim 1 comprising a reversing switch for reversing the direction of rotation of the second motor, said slide including a projection for acting on said reversing switch.

7. A system according to claim 6, wherein said projection has two ends and a ramp at each of said ends, the reversing switch comprising a rockable disc and two flexible strips on the disc one of which includes a stud for co-operation with said ramps.

8. A system according to claim 7, wherein at the end of the movement of the slide in the direction of returning a transparency into said magazine the reversing switch stops the motor controlling this movement, said system including a further circuit coupled to said reversing switch such that when a voltage is applied to the motor, the motor is rotated in the opposite direction to previous rotation.

9. A system according to claim 1 comprising information elements borne by said magazine and a channel having a base in which the magazine moves and including at least one contact adapted to cooperate with information elements so as to start the second motor.

10. A system according to claim 9, comprising a conductive layer covering the base of the magazine and a sliding contact in the circuit of the second motor and mounted in insulated manner on the base of the magazine, and wherein the information elements are conduct-

tive projections provided on said conductive layer covering the base of the magazine and electrically and permanently connected to said sliding contact.

5 11. A system according to claim 10 wherein the information elements are permanently mounted on the magazines in correspondence with each of the positions for transparencies in the magazine.

10 12. A system according to claim 11, wherein the information elements projections are disposed along the edge of the base of the magazine.

13. A system according to claim 9, wherein the information elements are projections integral with the base of the magazine.

14. A system according to claim 9, wherein said information elements are projections on the magazine, the contacts being disposed in a transverse row in the base of the channel in which the magazine moves so as to co-operate each with one of the projections which are offset from one another on the base of the magazine each 20 of the positions of transparencies in the magazine.

15 15. A system according to claim 1, comprising a reversing switch controlling the direction of movement of the magazine, and at least one element for controlling said reversing switch and projections on the magazine for 25 cooperating with said element to control said reversing switch.

16. A system according to claim 15, wherein said magazine has a base the projections being two in number and provided on the base of the magazine laterally offset 30 from one another at the front and the rear of the magazine base.

17. A system according to claim 15, wherein the element controlling the reversing switch is a three-armed rockable lever having two arms offset from one another 35 laterally in relation to the lateral offsetting of the projections on the magazine base while the third arm acts on the reversing switch element.

18. A system according to claim 17, wherein the third arm of the reversing switch control element bears a 40 magnet co-operating with soft iron elements forming part of the movable contact elements of the reversing switch.

19. A system according to claim 9, wherein the information elements borne by the magazine are studs so distributed longitudinally as to result in closure of the circuit of the second motor when each of the positions provided 45 for the transparencies in the magazine reaches a position for co-operating with the slide for moving the transparency from the magazine into the operative position.

20. A system according to claim 10, wherein each projection is disposed longitudinally on the magazine so as 50 to act on the contact which starts the second motor before the corresponding transparency reaches the loading slide movement axis, when the magazine is moved in the operative direction, and in that in the position in which 55 the transparency coincides with the slide movement axis the information projection on the magazine ceases to act on the contact.

21. A system according to claim 18, wherein the information elements borne by the magazine for closing the 60 supply circuit to the slide control motor are movable elements which can individually be brought into a position in which they are operative and another position in which they are inoperative.

22. A system according to claim 21, wherein the movable information elements adapted to occupy an inoperative or operative position are arranged to be brought into the operative position by the presence of a transparency frame in the magazine.

23. A system according to claim 18, comprising a 70 series of switches to provide selection of the transparency to be projected, each interposed in the circuit of the second motor in series with at least one switch disposed transversely to cooperate with one of the projections provided on the magazine base.

24. A system according to claim 23, wherein the switches are each formed by a strip engaging through an aperture in a rocking lever comprising a portion which bears a strip adapted to be brought into contact through the agency of the lever with a conductive band connected to the contactor.

25. A system according to claim 20, comprising push elements constituting the information elements on the rear face of the magazine and vertically slidably and each corresponding to a transparency recess.
